BATHING CAP

Clyde Maurice Moore, Richmond, Va., assignor to
Moorex Industries, Incorporated, Richmond,
Va.

Application April 10, 1947, Serial No. 740,583

18 Claims. (Cl. 2-68)

1

This invention relates to caps or head coverings and more particularly, to a beach bathing cap construction suitable to be used for swimming or other bathing purposes.

It is an object of the invention to provide a bathing cap which will effectively and efficiently prevent ingress of water to the hair of the wearer.

A further object of the invention is to provide a face and neck sealing band structure of elastic material which will conform to the contour of the skin, and which may be attached to a head covering of water-proof material to prevent ingress of water to the hair of the wearer.

Another object of the invention is to provide a face and neck sealing band of the aforementioned type having a series of beads, ridges, or the like, adapted to lie against the skin of the wearer.

An additional object of the invention is to provide a face and neck sealing band of the aforementioned type in which the band is split, and means are provided for connecting and disconnecting the margins of the split.

Another object of the invention is to provide a bathing cap construction comprising a face and neck sealing band of elastic material and a head covering connected thereto, said head covering being constructed of a water-proof material.

An additional object of the invention is to provide a bathing cap construction comprising a face and neck sealing band of elastic material, a head covering of water-proof material connected thereto, said head covering material having less elasticity than said band, a slit or opening extending through said band and into said head covering, and water-proof means for closing and opening said slit or opening.

A further object of the invention is to provide a bathing cap construction comprising a face and neck sealing band of elastic material, and a head covering of water-proof material connected thereto, in which the band only is split, and means are provided for connecting and disconnecting the margins of the split.

A further object of the invention is to provide a bathing cap construction comprising face and neck sealing marginal portions of highly elastic material and a head covering having less elasticity than said marginal portions.

An additional object of the invention is to provide a bathing cap of unitary elastic construction having marginal portions adapted to extend around the face and neck of the wearer, in which the marginal portions are molded in a constricted manner to insure a tighter fit around

2

said marginal portions than throughout the other portion of said cap.

A further object of the invention is to provide a bathing cap of unitary construction comprising highly elastic material throughout and including portions adapted to extend around the face and neck of the wearer.

An additional object of the invention is to provide a bathing cap construction comprising a head covering of waterproof material and a sealing band of elastic material adapted to extend down each side of the face, under the chin and around the neck of the wearer.

Other objects and advantages of the invention will become apparent as the description proceeds, reference being had to the accompanying drawings, wherein:

Fig. 1 is a side view showing one form of cap embodying features of the invention applied to the head;

Fig. 2 is a rear view of Fig. 1;

Fig. 3 is a lay-out plan view of the face and neck sealing band;

Fig. 4 is an enlarged sectional view of the band taken along the line 4-4 of Fig. 1, looking in the direction of the arrows;

Fig. 5 is an enlarged sectional view similar to Fig. 4 of a modified form of band;

Fig. 6 is an enlarged sectional view similar to Fig. 4 of another modified form of band;

Fig. 7 is an enlarged sectional view of the portion of the band extending under the chin of the wearer, taken along the line 7-7 of Fig. 3, looking in the direction of the arrows;

Fig. 8 is a side view showing a modified form of cap embodying features of the invention applied to the head;

Fig. 9 is an enlarged sectional view taken along the line 9-9 of Fig. 2 looking in the direction of the arrows;

Fig. 10 is a side view showing a still further modified form of cap embodying features of the invention applied to the head;

Fig. 11 is a fragmentary isometric view, parts being shown in section, of another modified form of my bathing cap;

Figs. 12 and 13 are enlarged sectional views similar to Fig. 4 of further modified forms of my bathing cap; and

Fig. 14 is a side view showing a still further modified form of my bathing cap applied to the head.

Referring to the drawings in detail, the bathing cap generally indicated by the reference numeral 1 in Figs. 1 and 2, comprises a relatively thin face

and neck sealing band, generally indicated by the numeral 2, which is preferably made of a highly elastic, moldable material such as rubber.

The face and neck sealing band 2 comprises a face sealing band portion 3, and a neck sealing band portion 4. The face sealing band portion 3 is preferably of a generally circular, oval, or heart shape, as illustrated in Fig. 3, and is adapted to extend across the forehead, down each side of the face, and under the chin of the wearer.

The neck sealing band portion 4 of the band 2 is adapted to extend around the neck of the wearer, and is preferably, but not necessarily, integrally connected to the face sealing band portion 3.

The preferred method of making the face and neck sealing band 2 is to mold the same as a unitary structure, substantially as illustrated in Fig. 3.

The peripheral length of the generally circular, oval, or heart shaped face band portion 3, and the length of the neck band portion 4, are preferably such that considerable stretching or tensioning of the highly elastic material in the band is maintained when in position on the face and neck of the wearer. This stretching or tensioning is desirable in order to maintain an absolutely effective seal and generally, an increase in the lengths of the band portions 3 and 4 of approximately 50% provides a highly effective seal without interfering with the comfort of the wearer. The value of 50% is given as an illustration, not as a limitation, since obviously the increase in the said lengths may vary widely. The specific said increase will depend to some extent upon the elasticity of the particular material used, and also, upon the personal likes and dislikes of the wearer. Further, the specific use of the cap will be a factor, e. g., shower bathing does not require the seal to be as effective as does beach bathing.

Referring now to Fig. 4, it will be seen that the face sealing band portion 3 is provided with a substantially circular stiffening and sealing projection or bead 5 at one edge thereof, and on its face contacting side with a plurality of transversely spaced projections 6 of substantially semi-circular shape in transverse cross-section, extending to adjacent the other edge thereof. The neck sealing band portion 4 is similarly constructed, and the said projections aid in providing an effective seal.

Preferably, the projections 6 of the face and neck band 2 gradually fade out as they approach the portion 7 of the band passing under the chin. In this portion of the band, the upper half thereof may be considered to be a portion of the face band 3, and the lower half thereof may be considered to be a portion of the neck band 4. The total width of this portion 7 of the band 2 however, is preferably less than the combined widths of the face and neck band portions 3 and 4.

As illustrated in Fig. 7, the portion 7 of the band 2 comprises the substantially circular beads 5 at each edge thereof, and an intermediate portion of relatively thick construction. The portion 7 of the band 2 is made thicker than the other portions thereof to resist or prevent folding due to movements of the chin of the wearer.

The face and neck sealing band 2 is suitably secured to a head covering 8 which is made of a water-proof material. In addition to being water-proof, the material of which the head covering 8 is made should have less elasticity than the band 2, and in fact, is preferably, but not

necessarily, substantially non-elastic. Examples of suitable materials are: rubberized silk or nylon, rubber having a relatively smaller degree of elasticity than the band 2, etc.

The head covering 8 forms the main body portion of the cap 1 and is desirably of one-piece construction although it may be made of several pieces if desired, and the pieces secured together in any suitable manner to render the construction water-proof, as by vulcanizing.

The head covering 8 is provided with a slit or opening 9 extending from an edge thereof inwardly of the covering. Preferably, but not necessarily, the slit or opening 9 is located substantially centrally of the rear portion of the head covering 8, and extends upwardly, substantially vertically, as illustrated in Fig. 2. Preferably, the slit or opening 9 is terminated below the crown of the head for a reason to be later described.

The head covering 8 is suitably secured to the face and neck band 2, as by vulcanizing, as indicated at 10, Fig. 4, and in assembled relation, the margins 11 and 12 of the neck band portion 4 are in alignment with the margins of the slit or opening 9.

Suitable means are provided for drawing the margins of the slit 9, and the margins 11 and 12 together when desired, and in the present instance, this means takes the form of a conventional separable fastener such as a "zipper" 13 having the usual slide 14.

Preferably, the "zipper" 13 is of water-proof construction, and may be of the type disclosed in Patent No. 1,991,943, granted to L. V. Keviczky on February 19, 1935, under the title, "Water-proof Closing Means," or of the type disclosed in Patent No. 2,124,206, granted to A. F. Mulka on July 19, 1938 under the title, "Dust-, Gas-, and Waterproof Sliding Clasp Fastener for Boots and Other Articles."

Referring now to Figs. 2 and 9, a generally triangular or trapezoidal shaped flap, gore or gusset 15, is suitably secured, as by vulcanizing, as indicated at 16, along one margin of the slit or opening 9. The flap 15 is preferably, but not necessarily, of the same material as the head covering 8, and may be, if desired, of unitary construction therewith.

The flap 15 is of sufficient width to completely cover the marginal portions of the slit 9, even when the said portions are separated and are being drawn together, and lies underneath the fastening means 13. Thus, the flap 15 performs a dual function. It prevents the hair of the wearer from becoming entangled in the fastening means, and also, it functions as a seal, or secondary seal, to prevent ingress of water through the slit or opening 9.

If desired, the free side of the flap 15 may be extended a sufficient distance beyond the slit 9 to effect a seal without the use of a water-proof "zipper." If so constructed, an ordinary "zipper" or other suitable fastening means may be used.

In placing the cap 1 on the head, the band 5 may be first placed under the chin and the cap then drawn rearwardly over the head. This operation causes a partial stretching or tensioning of the face band portion 3. Since, as stated above, the opening 9 preferably terminates below the crown of the head, the cap, in this position, is maintained on the head with little difficulty thereby leaving the hands of the wearer substantially free to next place the flap 15 in proper position and then draw the slide 14 of the "zipper" 13 downwardly to bring the margins of the slit

or opening 9 and the margins 11 and 12 of the neck band portion 4 together to close the cap. As stated previously, the head covering 8 has less elasticity than the band 2, and therefore as the slide 13 of the "zipper" 18 is drawn downwardly, an additional stretching or tensioning takes place in the face band portion 3, and also, the neck band portion 4 is stretched and placed under tension. Further, the side portions of the face band portion 3 are drawn rearwardly into proper position on the face.

The stretching or tensioning of the band 2 causes the face and neck band portions 3 and 4 to lie snugly against the skin around the face and neck of the wearer, thereby providing a highly effective and efficient seal preventing ingress of water under the cap to the hair of the wearer.

In the modified form of face band 3' illustrated in Fig. 5, the projections or ridges 6' have a triangular shape in transverse cross-section rather than a semi-circular shape as described above in connection with the band 3 illustrated in Fig. 4. A circular bead 5' is provided along one edge of the band 3' and the other edge thereof is vulcanized as indicated at 10, to the head covering 8. Obviously, the neck band may be similarly constructed.

In the modified form of face band 3'' illustrated in Fig. 6, the projections 6 and 6' of Figs. 4 and 5 are omitted, and further, the circular beads 5 and 5' are replaced by a streamlined or substantially tear-shaped bead 5''. The streamlined head 5'' is slightly more effective in deflecting water away from the edges of the band than the circular bead, and obviously, if desired, the streamlined bead 5'' may be substituted for the bead 5 or 5' of the band 3 or 3' of Fig. 4 or Fig. 5. The edge of the band 3'' opposite the bead 5'' is vulcanized as indicated at 10 to the head covering 8. The neck band may be similarly constructed.

The latter type face and neck band is particularly suitable for wearers having rather sensitive skins. The projections 6 and 6', in certain instances, leave "rings" around the face and neck of the wearer for a few minutes after the cap is removed, and for this reason the bands illustrated in Figs. 4 and 5 may be objectionable to certain wearers. Although there is some loss in the effectiveness and efficiency of the seal when the projections are omitted, an effective and efficient seal is still provided.

In the modified form of cap construction illustrated in Fig. 8, the bathing cap generally indicated by the reference numeral 1' comprises, as before, a head covering 8', and a face and neck band generally indicated by the numeral 2', suitably secured thereto as by vulcanizing.

The principal difference between this modified form of cap construction and the construction previously described is in the location of the "zipper." The head covering 8' may, if desired, be constructed of the materials previously described, and the face and neck bands 3' and 4' may take the form of any one of the band constructions previously described.

The head covering 8' differs from the head covering 8 in that the head covering 8' is of closed construction, i. e., the slit or opening 9 previously described is omitted.

With respect to the face and neck band 2', the neck band portion 4' thereof is made slightly longer than the neck band portion 4, and the ends thereof are overlapped and secured together as by vulcanizing.

Also, the face and neck band 2' is slit or split as indicated at 17, and suitable means such as the

"zipper" 18 is provided for connecting and disconnecting the margins of the split. The split 17 extends entirely through the face and neck band portions 3' and 4' and is preferably located so as to be on the left side of the face of the wearer.

The "zipper" 18 is provided with the usual slide 19 and may or may not be of water-proof construction. When, as illustrated in Fig. 8, the split 17 is spaced from the head covering 8' a sufficient distance to provide adequate sealing surface therebetween, a water-proof closure is not necessary since it is immaterial whether the portion of the face and neck of the wearer underlying the split gets wet.

In placing this form of cap on the head, the wearer places the cap on the head in the usual manner, and then, grasping the marginal portions of the neck band 4' adjacent the split 17, stretches or tensions the neck band 4' and brings these marginal portions together. At the same time some stretching or tensioning takes place in the face band 3'. The "zipper" slide 19 is then started on its track. Further closing movement of the slide 19 connects the margins of the split 17, and also, places the face and neck bands 3' and 4' under additional tension.

In this latter form of cap construction, since the stretching or tensioning action is applied directly to the face and neck band portions 3' and 4', and not through the head covering as in the previously described construction, the difference in elasticity between the head covering 8', and the face and neck sealing band 2' is not as important as in the previously described construction. The degree of elasticity of the head covering 8' may in fact equal that of the face and neck sealing band 2' and thus, if desired, the head covering 8' may be constructed of the same material as the face and neck sealing band 2'. Preferably, however, the head covering 8' has less elasticity than the band 2'.

Figure 10 illustrates one form of the invention in which the head covering 8' and the face and neck sealing marginal portions, generally indicated by the numeral 2' and comprising a face sealing band or marginal portion 3' and a neck sealing band or marginal portion 4', are of unitary construction as just described. In this form of construction, the entire cap is made of a highly elastic material such as previously described for the bands 2 and 2', and the "zipper" 18 may be omitted if desired. The band or marginal portions 3' and 4' are obviously not visibly defined in this modification.

In placing this latter form of cap on the head, if the "zipper" is omitted, the chin of the wearer may be placed in the neck aperture 20 and the marginal portion 4' stretched upwardly over the head and rearwardly whereby the face of the wearer will project through the face aperture 21, the marginal portions 3' and 4' providing an effective seal against the entry of water to the hair of the wearer.

Fig. 11 illustrates a slightly modified form of the cap illustrated in Fig. 10. In this form of the invention the head covering 8' and the marginal portions 2' of the cap are of unitary construction as the cap illustrated in Fig. 10, and of similar material, but the marginal portions 2', where connected to the head covering 8', are molded in a constricted manner to give a shirring effect as indicated at 22.

Fig. 12 illustrates a modified form of cap construction in which the band or marginal por-

tions 2⁴ are more resilient than the head covering 8⁴ although such difference is not defined by a visible band. In this form of the invention, the marginal portions 2⁴ are rendered more resilient or elastic than the head covering by compounding or by blending two different types of material as by the coagulation dip or similar methods well known to the rubber industry.

In the types of cap illustrated in Figs. 11 and 12, a "zipper" is not necessary and may be omitted if desired, as described in connection with the form of the invention illustrated in Fig. 10.

In the modified form of the invention illustrated in Fig. 13, the band 2⁵ and head covering 8⁵ are constructed of the same elastic material but the head covering 8⁵ is rendered less elastic than the band 2⁵ by reinforcement. As illustrated, the reinforcing is obtained by making the head covering 8⁵ or portions thereof of thicker construction than the band 2⁵. In this type of construction the cap preferably takes the form illustrated in Fig. 1, i. e., the "zipper" is provided at the back thereof.

The form of the invention illustrated in Fig. 14 is similar to that illustrated in Fig. 1 and differs therefrom only in that the band does not extend entirely across the forehead. Thus, as illustrated, the cap comprises a band 2⁶ of highly elastic material and a head covering 8⁶ of less elastic material.

The band 2⁶ comprises a face sealing band portion 3⁶ adapted to extend down each side of the face and under the chin of the wearer and a neck sealing band portion 4⁶ adapted to extend around the neck of the wearer.

A "zipper" 13' having a slide 14' is provided at the rear of the cap as described in connection with Fig. 1.

The bathing cap illustrated in Fig. 14, while not a preferred form of the invention, does provide an effective seal, particularly with respect to shower bathing and some forms of beach bathing. The central portion of the forehead is least vulnerable to leakage and hence, under certain conditions and for certain uses, this portion of the sealing band itself may be omitted. It is understood, of course, that in this (as well as all other forms of the invention) the head covering 8⁶ is of water-proof construction. Also, the head covering 8⁶ may be of elastic material, in which event the effectiveness of the seal across the forehead where the more elastic band is omitted, is increased.

It is to be noted that in each form of the invention the bathing caps may be considered to comprise a head covering of water-proof material having a face receiving aperture and a neck receiving aperture and adapted to completely house the hair and ears of the wearer, in which the neck and face receiving apertures (such as 20 and 21 of Fig. 10, for example) are provided marginally thereof or with marginal portions provided with the property of high elasticity.

While the invention is susceptible of various modifications and alternative constructions, I have shown in the drawings and have herein described in detail the preferred embodiments, but it is to be understood that I do not thereby intend to limit the invention to the specific forms disclosed, but intend to cover all modifications and alternative constructions falling within the spirit and scope of the invention as expressed in the appended claims.

This application is a continuation-in-part of my co-pending application Serial No. 674,170, filed June 4, 1946 now abandoned.

I claim:

5 1. A substantially water-proof bathing cap construction comprising, in combination; a face and neck sealing band of highly elastic water-proof material; said band comprising a face sealing band portion having a generally circular, oval or heart shape and adapted to extend across the forehead, down each side of the face, and under the chin of the wearer, and a neck sealing band portion adapted to extend around the neck of the wearer; a substantially non-elastic, 10 water-proof head covering secured to said face and neck sealing band; a slit or opening extending through said band and into said head covering; a flap connected to said head covering along one margin of said slit or opening; and means 15 for closing said slit or opening.

2. A substantially water-proof bathing cap construction comprising, in combination, a face and neck sealing band of highly elastic water-proof material, said band comprising a face sealing band portion adapted to extend across the forehead, down each side of the face and under the chin of the wearer, and a neck sealing band portion adapted to extend around the neck of the wearer; a substantially water-proof head covering secured to said face and neck band, said head covering having less elasticity than said face and neck sealing band; a slit or opening extending through said band and into said head covering; a flap connected to said head covering along one margin of said slit or opening; and means for closing said slit or opening.

3. A substantially water-proof bathing cap construction comprising, in combination, a face and neck sealing band of highly elastic water-proof material, said band comprising a face sealing band portion adapted to extend across the forehead, down each side of the face and under the chin of the wearer, and a neck sealing band portion adapted to extend around the neck of the wearer; a substantially water-proof head covering secured to said face and neck band, said head covering having less elasticity than said face and neck sealing band; a slit or opening extending through said band and into said head covering; and water-proof means for closing said slit or opening.

4. A substantially water-proof bathing cap construction comprising, in combination, a face and neck sealing band of highly elastic water-proof material, said band comprising a face sealing band portion adapted to extend in a continuous manner across the forehead, down each side of the face and under the chin of the wearer, and a neck sealing band portion adapted to extend around the neck of the wearer; a substantially water-proof head covering secured to said face and neck band, said head covering having less elasticity than said face and neck sealing band; a slit extending through said band; and means for connecting and disconnecting the margins of said slit.

5. A substantially water-proof bathing cap construction comprising, in combination, a face and neck sealing band of highly elastic water-proof material, said band comprising a face sealing band portion adapted to extend in a continuous manner across the forehead, down each side of the face and under the chin of the wearer, and a neck sealing band portion adapted to extend around the neck of the wearer; a substan-

tially water-proof head covering secured to said face and neck band, said head covering having less elasticity than said face and neck sealing band; a slit extending through said face and neck sealing portions of said band; and means for connecting and disconnecting the margins of said slit.

6. For use in a substantially water-proof bathing cap construction, a face and neck sealing band of highly elastic water-proof material, said band comprising a face sealing band portion adapted to extend in a continuous manner across the forehead, down each side of the face and under the chin of the wearer, and a neck sealing band portion adapted to extend around the neck of the wearer, the portion of the band extending under the chin of the wearer having a thicker construction than the other portions of said band.

7. For use in a substantially water-proof bathing cap construction, a face and neck sealing band of highly extensible water-proof material, said band comprising a face sealing band portion adapted to extend in a continuous manner across the forehead, down each side of the face and under the chin of the wearer, and a neck sealing band portion adapted to extend around the neck of the wearer, the said face and neck sealing band portions each having a length normally less than that required to surround the face and extend around the neck, respectively, of the wearer; whereby considerable stretching or tensioning of the highly extensible material in the band is maintained when in position surrounding the face and extending around the neck of the wearer.

8. A substantially water-proof bathing cap construction comprising, in combination, a face and neck sealing band of highly elastic water-proof material, said band comprising a face sealing band portion adapted to extend down each side of the face and under the chin of the wearer, and a neck sealing band portion adapted to extend around the neck of the wearer; a substantially water-proof head covering secured to said face and neck band, said head covering having less elasticity than said face and neck sealing band; a slit or opening extending through said band and into said head covering; a flap connected to said head covering along one margin of said slit or opening; and means for closing said slit or opening.

9. A substantially water-proof bathing cap construction comprising, in combination, a face and neck sealing band of highly elastic water-proof material, said band comprising a face sealing band portion adapted to extend down each side of the face and under the chin of the wearer, and a neck sealing band portion adapted to extend around the neck of the wearer; a substantially water-proof head covering secured to said face and neck band, said head covering having less elasticity than said face and neck sealing band; a slit or opening extending through said band and into said head covering; and water-proof means for closing said slit or opening.

10. For use in a substantially water-proof bathing cap construction, a face and neck sealing band of highly extensible water-proof material, said band comprising a face sealing band portion adapted to extend in a continuous manner down each side of the face and under the chin of the wearer, and a neck sealing band portion adapted to extend around the neck of the wearer, the said face and neck sealing band portions each having a length normally less than that required to substantially surround the face and extend around

the neck, respectively, of the wearer; whereby considerable stretching or tensioning of the highly extensible material in the band is maintained when in position substantially surrounding the face and extending around the neck of the wearer.

11. A substantially water-proof bathing cap construction comprising a substantially water-proof head covering including face and neck sealing marginal portions of highly extensible material, said marginal portions comprising a face sealing portion adapted to extend in a continuous manner across the forehead, down each side of the face and under the chin of the wearer, and a neck sealing portion adapted to extend around the neck of the wearer, the said face and neck sealing portions each having a length normally less than that required to surround the face and extend around the neck, respectively, of the wearer; whereby considerable stretching or tensioning of said highly extensible material is maintained when in position surrounding the face and extending around the neck of the wearer.

12. A substantially water-proof bathing cap construction comprising a substantially water-proof head covering including face and neck sealing marginal portions of highly extensible material, said marginal portions comprising a face sealing portion adapted to extend in a continuous manner across the forehead, down each side of the face and under the chin of the wearer, and a neck sealing portion adapted to extend around the neck of the wearer, the said face and neck sealing portions each having a length normally less than that required to surround the face and extend around the neck, respectively, of the wearer; whereby considerable stretching or tensioning of the highly extensible material is maintained when in position surrounding the face and extending around the neck of the wearer;

40 said head covering being constructed of the same material as said face and neck sealing marginal portions.

13. In a substantially water-proof bathing cap construction, the combination comprising a substantially water-proof head covering including a face and neck sealing marginal portion of highly extensible material, said head covering being adapted to house the hair and ears of the wearer and said marginal portion thereof being adapted to extend about the neck, upwardly along each side of the face and across the forehead of the wearer, said marginal portion of highly extensible material having a length normally less than that required to extend about the neck, upwardly along each side of the face and across the forehead of the wearer, whereby considerable stretching or tensioning of the highly extensible material is maintained when in position about the neck, upwardly along each side of the face and across the forehead of the wearer.

14. For use in a substantially water-proof bathing cap construction, a face and neck sealing band of highly elastic water-proof material, said band comprising a face sealing band portion adapted to extend in a continuous manner down each side of the face and under the chin of the wearer, and a neck sealing band portion adapted to extend around the neck of the wearer, the portion of the band extending under the chin of the wearer having a thicker construction than the other portions of said band.

15. A substantially water-proof bathing cap construction comprising, in combination, a face and neck sealing band of highly elastic water-proof material, said band comprising a face seal-

ing band portion adapted to extend in a continuous manner across the forehead, down each side of the face and under the chin of the wearer, and a neck sealing band portion adapted to extend around the neck of the wearer, projection means on the face and neck sealing band portions of said band; a substantially waterproof head covering connected to said face and neck band, a slit extending through said face and neck sealing portions of said band; and means for connecting and disconnecting the margins of said slit.

16. A substantially water-proof bathing cap construction comprising, in combination, a face and neck sealing band of highly elastic waterproof material, said band comprising a face sealing band portion adapted to extend in a continuous manner across the forehead, down each side of the face and under the chin of the wearer, and a neck sealing band portion adapted to extend around the neck of the wearer, a substantially water-proof head covering connected to said face and neck band, a slit extending through said face and neck sealing portions of said band; and means for connecting and disconnecting the margins of said slit

17. A substantially water-proof bathing cap construction comprising a substantially waterproof head covering and a face and neck sealing band of highly extensible water-proof material, said head covering having less elasticity than said face and neck sealing band, said band comprising a face sealing band portion adapted to extend in a continuous manner across the forehead, down each side of the face and under the chin of the wearer, and a neck sealing band portion adapted to extend around the neck of the wearer, projection means on the face and neck sealing band portions of said band, the said

face and neck sealing band portions each having a length normally less than that required to surround the face and extend around the neck, respectively, of the wearer; whereby considerable stretching or tensioning of the highly extensible material in the band is maintained when in position surrounding the face and extending around the neck of the wearer.

18. A bather's cap involving: a head conforming cap having openings for the face and neck of the wearer, and defining at least one slit extending from the neck to the crown of the cap; a chin strap separating said face and neck openings; a gore set in said slit and sealed to a margin thereof, and a continuous fastener means extending the length of said slit for drawing the margins of said slit into juxtaposition, and co-acting with said chin strap when said fastener means is closed to cause the margins of said neck opening to conform closely to the neck of the wearer.

C. MAURICE MOORE.
